PORTABLE DICTATING MACHINE

Gordon Severson, Detroit, Mich., assignor to Minnesota
Mining and Manufacturing Company, St. Paul, Minn.,
a corporation of Delaware

Filed Dec. 24, 1959, Ser. No. 58,809

Term of patent 14 years

(Cl. D26—14)

FIG.3

FIG.4

FIG.2

FIG.5

FIGURE 1 is a perspective view of a portable dictating machine incorporating my new design, looking at the machine from the front thereof.

FIGURE 2 is a perspective view thereof, looking at the machine from the back.

FIGURE 3 is a side view thereof.

FIGURE 4 is a front end view thereof on a reduced scale.

FIGURE 5 is a back end view thereof on a reduced scale.

I claim:

The ornamental design for a portable dictating machine, substantially as shown and described.
